UNITED STATES PATENT OFFICE.

WILLIS MARSHALL, OF CHICAGO, ILLINOIS.

GRAIN-BINDER.

SPECIFICATION forming part of Letters Patent No. 341,589, dated May 11, 1886.

Application filed April 11, 1885. Serial No. 161,950. (No model.)

To all whom it may concern:

Be it known that I, WILLIS MARSHALL, of Chicago, in the county of Cook and State of Illinois, have invented certain new and useful 5 Improvements in Grain-Binders, of which the following is a specification.

In the present type of Appleby binders, now so well known to those skilled in the art to which the present invention belongs, the binding mechanism is thrown into action (whenever a predetermined resistance is opposed to the packers as they force the grain into the binding-receptacle) by means of a tripping-lever engaging the hub or the body portion of 15 a tripping-dog, which in turn acts to release a clutch otherwise held out of contact with a constantly-moving part of the binder. As this type of binder is now generally manufactured the tripping-dog is loosely mounted 20 upon the binder-arm shaft on the end nearest the train of the gearing which operates the binding mechanism, and is held yieldingly depressed and in position to perform its office while the binder is at rest by means of a spiral spring exerting its expansive force in a 25 direction coincident with the axis of the coil, the spring being held in place by a bolt or rod passing through the body of the tripping-dog, and screw-threaded on one end for the reception 30 of an adjusting-nut and pivotally connected at its other end with the crank of the binder-arm shaft. This construction of the tripping-dog and spring and their mode of connection, while ordinarily answering the 35 purpose intended, has been found objectionable in several particulars. The dog is materially weakened by the hole bored through it for the reception of its spring-retaining bolt, necessitating increased thickness and strength 40 of material and consequently increased cost of manufacture. The constant friction of the spring-retaining bolt upon the sides of the hole gradually increases its diameter, so that the spring will slip through and become inoperative, and the mode of adjusting the tension of the 45 spring is slow and awkward and involves the use of a wrench.

My invention is designed to remedy these objections, and, while retaining all the advantages of the old construction, to improve upon it in the way of producing a stronger tripping-

dog, and one that is not liable to wear and render its depressing-spring inoperative; in dispensing with certain parts needed in the old construction, and in affording a spring whose 55 adjustment is quickly effected without the use of tools.

To these ends my invention consists in an improved form of tripping-dog, and in a novel arrangement therewith of its depressing-spring. 60

In the drawings, Figure 1 is a side view of so much of a binder as is needed to show my invention; Fig. 2, a view of the parts shown in Fig. 1, looking in the direction of the arrow, and Figs. 3 and 4 side and top views, respectively, of my improved tripping-dog and spring detached from the binder. 65

A is the tripping-dog, which may be cast or otherwise made in the form shown in Figs. 3 and 4, with a hub, a, to fit loosely over the 70 binder-arm shaft and sufficiently elongated to serve as a bearing for the coiled spring B, and with a flange or arm, a', having notches or teeth for the engagement of one end, b', of the spring. In other respects the dog is similar to 75 the old form.

The spring B may be simply bent once or may be of any desired number of coils, and is fitted over the elongated hub of the tripping-dog, its end b being connected in any suitable 80 manner to the crank-arm d of the binder-arm shaft D, or it may be to the shaft itself, and its end b' extended over and engaged with the notches or teeth on the flange a' of the tripping-dog. This end b' is bent downward near 85 its extremity, so as to form a hook for easier manipulation when it is desired to increase or diminish the tension of the spring by changing from one notch to another; but of course this may be dispensed with, as the straight end 90

would answer the purpose.

To apply the spring, it is only necessary to disconnect the pitman E from the crank d and slip it over the crank to its place on the tripping-dog hub. It will thus be seen that in 95 case of breakage a new spring can be readily substituted in short time.

The binder-arm C and the clutch F G are connected with their respective parts and operated therewith, as usual, and the latter engages with the tripping-dog according to the original way in the Appleby binder. 100

From this description it will be seen that I dispense with the spring-retaining bolt, the objectionable features of which I have already pointed out; that I am able to effect a quick adjustment of the depressing-spring without the use of tools; that in case of breakage of the spring it can be easily replaced, and that my improved tripping-dog is not liable to break, as in the old form.

10 While I have shown the tripping-dog similar to the old, except wherein I have discriminated, it is obvious that my improvements could be made with one of different contour. For instance, the flat portion a^2 , absolutely necessary in the old form for the reception of the spring-retaining bolt, can be entirely dispensed with; and while I have shown the hub of the dog as elongated for the reception therein of the depressing-spring, it is obvious that 15 this hub may be shortened and the spring slipped into place directly onto the binder-arm shaft intermediate the crank-arm thereof and the tripping-dog; but while these and other modifications will occur to those familiar

with the art without departing from the spirit 25 of my invention, the form shown I consider most desirable.

Having thus described my invention, what I claim is—

1. A tripping-dog for grain-binders, cast 30 with or having attached thereto a notched arm or flange, for the purpose described.

2. A tripping-dog for grain-binders constructed as described with an elongated hub for the reception of its depressing-spring, and 35 a notched arm or flange with which an effective end of said spring engages.

3. The combination as hereinbefore set forth, with the clutch member of a grain-binding mechanism, of the tripping-dog, its depressing spring having one of its ends fast to the binder-arm shaft or its crank, and its other end engaging the notched flange on the dog. 40

WILLIS MARSHALL.
